TRUNDLE TOY

Herman G. Fisher, Leslie W. Sly, and Walter P. Doe, East Aurora, N. Y., assignors to Fisher-Price Toys, Inc., East Aurora, N. Y.

Application November 20, 1951, Serial No. 17,476

Term of patent 14 years

(Cl. D34—15)

To all whom it may concern:

Be it known that we, Herman G. Fisher, Leslie W. Sly, and Walter P. Doe, citizens of the United States, residing at 861 Chestnut Hill Road, East Aurora; 89 North Grove Street, East Aurora, 292 Center Street, East Aurora, respectively, in the county of Erie and State of New York, have invented a new, original, and ornamental Design for a Trundle Toy, of which the following is a specification, reference being had to the accompanying drawing, forming part thereof.

Fig. 1 is a perspective view of a trundle toy, showing our new design;

Fig. 2 is an end elevational view thereof, on a larger scale; and

Fig. 3 is a developed view of the cylindrical center portion thereof, on a larger scale.

The dominant features of our new design are shown in solid lines in the drawing. The dotted

line showing of a handle and bale has been omitted from Fig. 2 for convenience of illustration. The drawing figures are shaded to indicate color contrast.

We claim:

The ornamental design for a trundle toy, as shown and described.
